ABSTRACT: A body massager and/or cosmetic applicator which includes a base member having a plurality of openings formed therein in which a ball-type roller is retained for relative rotation. The arrangement is such that the peripheral portion of each ball roller is extended to at least one side of the base member whereby the ball rollers may be placed in rolling engagement with that part of the body to be massaged and/or to which a cosmetic or beauty cream is to be applied.

BODY MASSAGER AND/OR COSMETIC APPLICATOR

THE PROBLEM

It has been long recognized that regular applications of beautifying body creams and/or lotions, and massage to one's face or body are extremely helpful in maintaining one's care and beauty. Heretofore it was customary to apply such beautifying creams, cosmetics and lotions to one's face or body by simply spreading such creams or cosmetics over the face or body by hand. However, this manner of application required the soiling of one's hands with such lotion or cream, thereby preventing one from performing other acts or functions with the hands until the task of applying the cream or lotion was completed and/or the hands wiped or washed.

OBJECTS

It is, therefore, an object of this invention to provide an applicator-massager for applying a body lotion or cream to the face or portions of the body in a manner in which the hands are not required to be soiled.

Another object of this invention is to provide an improved cosmetic applicator which is capable of effecting a massaging operation to the face or body as the cosmetic is being applied.

Another object of this invention is to provide a means for massaging the face or a portion of the body for relieving tension and/or muscular aches, pains and discomforts due to stress and strains.

Another feature of this device resides in the provision that the cosmetic applicator and massager is relatively simple in structure, can be easily fabricated, and is positive in operation.

SUMMARY OF INVENTION

In accordance with this invention the foregoing objects and other features and advantages are attained by an applicator and massager comprising of a rigid base member having an enlarged head end and a connected handle end portion. The applicator end portion of the member is provided with a plurality of openings with means disposed therein for retaining a ball roller for relative rotation therein. The arrangement is such that a peripheral portion of the ball rollers extend to at least one side of the applicator end portion so that in operation the ball rollers may be disposed into rolling engagement with that portion of the face or body to be massaged and/or to which the cosmetic or cream is to be applied.

FEATURES

A feature of this invention resides in the provision wherein the means for retaining the ball roller for relative rotation within their respective retainers are specifically constructed so as to effect positive retention of the ball rollers, yet allowing the ball rollers to be readily removed for easy assembly and/or cleaning or replacement.

Another feature of this invention resides in the provision wherein massage applicator can be constructed so as to define a closure or cover for the container in which the cream or cosmetic to be applied is distributed and/or dispensed.

Another feature of this invention resides in the provision that the ball rollers may be provided with either a smooth surface and/or an irregular or ridged surface.

Other features and advantages will become more readily apparent when considered in view of the drawings and specification in which:

FIG. 1 illustrates a plan view of the applicator constructed in accordance with this invention.

FIG. 2 is a sectional view taken along line 2-2 on FIG. 1.

FIG. 3 is a detail view of the ball roller illustrating a modified form of the invention.

FIGS. 4 and 5 illustrate other modified forms of ball construction applicable for use in this invention.

FIG. 6 illustrates the invention as applied to a closure or cover for a jar in which a body lotion or cream is distributed.

Referring more specifically to the drawings, FIG. 1 illustrates an embodiment of a massage-applicator 10 constructed in accordance with the present invention. As shown the massage-applicator 10 comprises a rigid base member 11 having an enlarged head end or applicator-massager end portion 11A and an integrally connected handle end portion 11B. It will be understood that the rigid base member 11 may be formed of any suitable material as for example plastic, metal and/or the like. However, for purposes of economy it is preferred that the base member 11 be formed of suitable plastic material. Formed in the head end portion 11A of the base member 11 are a plurality of apertures or openings 12. In the illustrated form three such apertures or openings 12 are provided. However, it will be understood that the number of apertures 12 may be varied as may be desired.

Disposed within each of the apertures 12 is a retaining means 13 as in FIGS. 1 and 2. Each retaining means 13 comprises an annular or cylindrically shaped member which is suitably secured to the periphery of the respective opening 12 intermediate the ends thereof. One end 13A of the retainer 13 is inwardly turned to define a spherical seat 14 conforming to a peripheral portion of a ball roller 15 adapted to be retained in the seat of the retainer means. The other end 13B of the ball retainer 13 defines a cylindrical section having an inturned bead or lip 16 circumscribing the inner periphery thereof which forms the means for retaining the ball 15 within the retainer 13. The arrangement is such that each of the ball rollers 15 is retained in free rolling engagement with respect to the retainer with a peripheral or portion of the ball's surface extending beyond the ends 13A, 13B of the retainer 13. As shown, the internal diameter of the cylindrical portion 13B of the retainer means 13 is equal to at least the major diameter of the ball 15 with the ball 15 being retained in rolling relationship between the spherical seat 14 and lip or bead 16.

In the illustrated construction the major diameter of the ball is confined between the lip 16 and the seat 14. Because one end 13B is sized to the diameter of the ball 15, it will be noted that the balls 15 can be readily removed from their respective retainers for replacement, repair, cleaning and/or the like, simply by applying slight pressure on the end of the ball extending beyond the spherical seat end 13A of the retainer means 13. The ease with which the balls can be popped into and out of their respective retainers facilitates assembly.

It is to be noted that a peripheral portion or surface of the ball extending to one side of the major diameter extends beyond the ends 13A, 13B of retainers so that the balls can be placed in rolling engagement with the surface or skin of the body when the device 10 is placed in operation. In operation the applicator-massager 10 is utilized to apply body creams or lotions to the body merely by placing or scooping some cream or lotion on the applicator end portion 11A and thereafter placing the applicator with cream or lotion thereon to one's body so that the ball rollers are disposed in rolling engagement with a portion of the body to which the cream or lotion is to be applied. Application of the cream to the body is effected by moving the applicator over the face or body with the ball rollers 15 in rolling engagement with the face or body. In this manner the cream is uniformly spread over the surface of the body and at the same time, depending upon the applied pressure, massaging the body to stimulate blood circulation therethrough.

It will be noted that in operation the portion of the ball rollers extending beyond end 13B of the retainer is placed against the body. Therefore, reaction of the applied pressure tends to force the ball rollers 15 against the seat 14, thereby prohibiting any unintentional popping of the ball from its retainer when in use.

It will be noted that the periphery of the balls 15 may be provided with a smooth surface as shown in FIGS. 1 and 2 or the surface of the ball rollers 15A may be provided with a series of circumscribing grooves 20. As seen in FIG. 3, the circumscribing grooves 20 are arranged over the surface of the ball 15A so that no more than two grooves will intersect at any

given point. In this manner the major circumference of the ball roller 15A is maintained at all times to provide a surface that can be retained in smooth, rolling engagement with respect to the retainer 13.

In another form of the invention the ball rollers 15B may be provided with a series of circumscribing ridges 21. In this arrangement the ridges define the major circumference of the ball rollers which maintain the ball 15B in freely rotatable relationship within the retainer 13.

In another form of the invention the applicator 25 may be constructed so as to define a cover or closure for the jar or container 26 in which the cosmetic or lotion is distributed. As best seen in FIG. 6, the cosmetic jar 26 comprises a container having an open end which may be provided with either external or internal thread or the like 27. The applicator 25 in this form of the invention comprises a lid or closure having a circumscribing depending wall 25A which may suitably be threaded to engage with the threads 27 circumscribing the jar opening 26A. The applicator 25 is thus detachably secured to the jar 26 in the nature of a lid or closure.

The surface portion of the lid or closure 25 as illustrated in FIG. 6 is provided with a plurality of openings 28 each having a retainer 29 secured therein in a manner similar to that hereinbefore described with respect to FIGS. 1 and 2, and a ball roller 30 is disposed in each of the retainers 29, as hereinbefore described. Accordingly, it will be noted that in application and use the cover or lid 25 may be alternately employed as an applicator-massager as described with respect to FIGS. 1 and 2. In this form of the invention an applicator-massager may be conveniently dispensed with each jar of cosmetic cream.

While the invention has been described with respect to particular embodiments thereof, it will be readily appreciated and understood that variations and modifications may be made without departing from the spirit or scope of the invention.

I claim:

1. A massage applicator comprising:
a rigid base member having a plurality of openings formed therein;
a retainer means secured in each of said openings; and
massage means retained in said retainer means for free relative movement with respect to said retainer means, said massage means having a peripheral portion thereof extending to at least one side of said retainer means, each of said retainer means including a ring member, said massage means comprising a spherically shaped roller retained for free relative rotation in each of said retainer ring members whereby each of said rollers is free to rotate within its respective ring member when said applicator-massager is applied to a portion of the body to be massaged, and said ring member including a cylindrical member having one end inwardly deformed to define a spherically shaped seat extending to one side of the major

circumference of the roller, and said other end of said cylindrical member extending to the other side of the major circumference of said roller, and said other end having an internal bead for retaining said roller within said retainer.

2. The invention as defined in claim 1 wherein said roller is releasably retained within said cylindrical retainer member.

3. The invention as defined in claim 1 wherein said rigid base member includes an enlarged head end portion in which said openings are formed, and a connected reduced handle portion to facilitate the manipulation of said massage-applicator.

4. The invention as defined in claim 1 wherein at least one of said rollers includes a roughened surface.

5. The invention as defined in claim 4 wherein said roughened surface of said roller is defined as a plurality of intersecting grooves circumscribing the surface of said roller.

6. The invention as defined in claim 5 wherein not more than two such grooves intersect at any given point.

7. The invention as defined in claim 4 wherein said roughened surface is defined as a series of circumscribing intersecting ridges projecting outwardly from the surface of said roller, said ridges being of substantially uniform height.

8. The invention as defined in claim 1 wherein said rigid base member comprises a jar cover.

9. The invention as defined in claim 1 wherein said base member includes a depending circumscribing flange having a thread portion by which said member is adapted to be threadedly engaged with a jar.

10. In combination with a receptacle adapted to contain a cosmetic material, and a cover therefor comprising:

a rigid member adapted to form a cover for said receptacle; said rigid member having a plurality of openings spatially disposed in the plane thereof; a ring-shaped retainer connected to said member in each of said openings; said retainer including a cylindrical section having a length which is less than the diameter thereof; said cylindrical section extending to at least one side of base member;

one end of said section being inwardly deformed to define a spherical seat;

a ball-shaped roller disposed within said retainer to engage said seat;

said cylinder having its other end extending beyond the major circumference of said roller; and

said other end having an internal bead for frictionally retaining said roller in rolling engagement within said ring whereby a surface portion of said roller extends beyond the internal bead of said retainer so that said rollers can be disposed in rolling engagement with a portion of the body to be massaged.
